Primary Examiner — Ralf Seifert(74) *Attorney, Agent, or Firm* — Bush Intellectual Property Law; Kenneth M. Bush(57) **CLAIM**

We claim the ornamental design for a demount tool, as shown and described.

DESCRIPTION

FIG. 1 is a top front right perspective view of a demount tool showing our new design;

FIG. 2 is a top rear left perspective view thereof;

FIG. 3 is a bottom front left perspective view thereof;

FIG. 4 is a bottom rear right perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof; and,

FIG. 10 is a right side elevation view thereof.

The ornamental design for a demount tool for uncoupling a water pipe from a water pipe coupling.
